A. H. BEST.

BURNER.

APPLICATION FILED JUNE 3, 1919.

1,351,550.

Patented Aug. 31, 1920.

UNITED STATES PATENT OFFICE.

ANNIE H. BEST, OF BROOKLYN, NEW YORK, ASSIGNOR TO W. N. BEST, INC., OF NEW YORK, N. Y., A CORPORATION OF NEW YORK.

BURNER.

1,351,550.

Specification of Letters Patent. Patented Aug. 31, 1920.

Application filed June 3, 1919. Serial No. 301,523.

To all whom it may concern:

Be it known that I, ANNIE H. BEST, a citizen of the United States, and a resident of Brooklyn, in the county of Kings and State 5 of New York, have invented certain new and useful Improvements in Burners, of which the following is a specification.

This invention is an improvement in burners for hydrocarbon or other liquid or 10 semi-liquid fuels in which the fuel is sprayed or delivered in atomizers or vaporizers formed by the action of a jet of some expandible gaseous medium, such for instance, as steam or compressed air. My 15 invention is an improvement on the type of burner shown in the Best Patents 708,453, and 752,195. In the constructions shown in said patents, there is provided a fuel passage terminating in an upwardly directed 20 outlet and a passage for the expandible gaseous spraying medium terminating in an outlet directed substantially at right angles across the fuel outlet. The steam or air passage has a mouthpiece normally clamped in 25 position but movable upwardly to facilitate cleaning or the removal of obstructions within the outlet.

My invention relates primarily to the construction of this movable mouthpiece and its 30 connection to the remainder of the burner and its operating mechanism, so that the mouthpiece may be moved to free the outlet from obstructions without raising it away from the supporting surface with 35 which it coöperates to form the gaseous medium outlet. By means of my construction, it is possible to adjust the position of the gaseous medium outlet toward or from the fuel outlet without varying the sizes thereof, 40 and without interfering with the operation of the burner. Should scale or other foreign substance clog the atomizer orifice, it can be removed by loosening the securing means and allowing the movable mouthpiece or 45 atomizer lip to pass over the fuel outlet so that the substance clogging the passage will be deposited in the fuel orifice. Upon the return of the mouthpiece or atomizer lip to its original position, the operation of the 50 burner will cause the foreign substance to pass out with the fuel. The construction is such that carbon can not form nor solidify over the atomizer and the atomizer lip has a sliding connection of such form that in 55 being adjusted, it does not leave its seat as

is the case when it is swung or raised as in the prior patents above referred to.

In the accompanying drawings to which reference is to be had, I have shown certain forms which my invention may assume, although it is evident that I do not wish to be restricted to such specific constructions.

In these drawings:

Figure 1 is a central longitudinal section through a burner constructed in accordance 60 with my invention, and particularly adapted for small sizes, said section being taken on the line 1—1 of Fig. 2.

Fig. 2 is a top plan view of the construction shown in Fig. 1.

Fig. 3 is a face view.

Fig. 4 is a view similar to Fig. 1 but showing a different embodiment, particularly adapted for large sizes, as for instance, the heating of locomotives, and

Fig. 5 is a top plan view of the form shown in Fig. 4.

In the burner shown in Figs. 1, 2, and 3, I employ a body portion 10 preferably formed from a single casting of brass or 80 other suitable material, and having passages 11, and 12 therethrough, the former being for the liquid or semi-liquid fuel and the latter for the steam, compressed air, or other atomizing fluid. Each of these passages has 85 a threaded inlet or other construction adapting it for attachment to suitable supply pipes. The fuel passage 11 has an upwardly facing outlet 13, terminating in a flat face or table portion 14 of the burner. 90 The outer wall of the passage is cut away or formed with a recess 15 below the plane of the surface 14 and flaring somewhat as shown particularly in Fig. 2.

The passage 12 for the atomizing medium 95 terminates in an outlet orifice 16 formed between the surface 14 and a movable mouthpiece or atomizer lip 17. This orifice is preferably slightly wider than the fuel outlet orifice 13, and is preferably slightly higher 100 at its side edges than at its middle portion as shown particularly in Fig. 3, so that the resulting fan-shaped spray or sheet of fuel will be substantially of the same thickness at the side portions as at the middle portion. The 105 atomizer lip is mounted so that it may slide along the surface 14 in a direction at right angles to the outlet 13 and may thus approach or recede from the latter without varying the size or shape of the atomizer 110

orifice 16. The member 17 is shown as fitting into a recess beneath an upper flange 18 which prevents it from moving away from the surface 14 and has suitable operating means 5 movable back and forth within said recess. This operating means is shown as a bolt 19 extending through a passage in the body of the burner and rigidly secured to the member 17. The bolt at its rear end has 10 a nut 20 by the tightening of which the mouthpiece may be drawn back to its limiting position. As it is not ordinarily desirable to permit the member 17 to move entirely out of the recess or to be separated 15 from the balance of the burner, the bolt preferably has a cotter pin 21 limiting the movement of the nut 20. The relative proportions of the parts is such that by screwing the nut back so that it engages the cotter pin, the member 17 may move forward until the atomizer orifice 16 is over the fuel orifice but the member 17 will still be held down by the flange 18. The flange 18 may if desired be entirely omitted, and other means utilized 20 for preventing the upward movement of the mouthpiece. The body has a pair of dowel pins 22 disposed within corresponding recesses in the mouthpiece so as to guide the mouthpiece and prevent any upward movement 25 of the latter. These will hold the mouthpiece down in proper position even though the mouthpiece be moved out beyond the flange 18 or even though the latter be omitted. The rear or inner surface of the 30 recesses and the corresponding surface of the mouthpiece are shown as being beveled or inclined downwardly and inwardly so that when the mouthpiece is drawn back to its limiting position, it will at the same time 35 be forced downwardly and held firmly against the supporting surface 14 of the burner. Thus the tightening of the nut not only holds the atomizer lip tightly to the body of the burner but also furnishes the 40 desired pressure to hold the atomizer lip down and insure the joint being hermetically sealed. The flange 18 not only serves to hold the mouthpiece down but protects these inclined surfaces and prevents any foreign 45 substance from falling from the fire box and getting in between the atomizer lip and the body of the burner when the nut and the bolt are loosened.

It will be noted that the bolt 19 does not 50 pass through the expansive fluid passage 12 but through a separate and independent passage in the wall of the burner. The inclined rear surface of the nozzle piece seats 55 against the inclined surface of the burner both above this bolt and below it so that no packing of any kind is required for the bolt, and the steam or other expansive fluid cannot gain access to the bolt passage when the nozzle member is in place.

60 In the larger construction shown in Figs.

4 and 5, the same principle of operation is employed although the details are somewhat different. Due to the greater width of the mouthpiece 17^a, this is provided with two parallel clamping bolts 19^a—19^a. These may 65 extend through lugs or flanges 23 and 24 instead of through passages in the body of the burner as shown in Fig. 1. Instead of having the bolts rigidly secured to the mouthpiece, the latter may have slots 25 therein 70 receiving the square heads 26 of the bolts. By removing the cotter pins 21, and entirely removing the nuts 20, the mouthpiece may be moved out entirely beyond the end of the body 10^a and then lowered out of operative 75 engagement with the bolts. In this form, the body 10^a has formed integral therewith lugs 27 whereby the burner may be clamped, or otherwise secured in position, and the inlet to the fuel passage 11^a is shown as extending up from the bottom and the inlet to the atomizing passage 12 extending in from the side instead of both from the rear as in Fig. 1.

My improved construction is cheap, durable, and made of a minimum number of parts. The outlets may be so formed as to give any desired width of flame by varying the flare of the recesses 15 shown in Fig. 2 or this flare may be eliminated and the sides 90 made straight as shown in Fig. 5 so as to give a long straight flame. The outlet for the expansive fluid being wider than the liquid fuel outlet, the expansive fluid thoroughly covers the fuel outlet and prevents 95 any droiling or dribbling of fuel from the nose of the burner. When a short flame is desired, the opening for the expansive fluid is very small in height but when a long flame is required the opening is proportionately 100 larger or higher so that the flame may extend the full length of the furnace or fire box in connection with which the burner is 105 used.

In my improved construction the steam, compressed air or other expansive fluid in escaping across the liquid fuel outlet exerts not only an atomized or vaporized action, but also exerts a limited pressure on the liquid in the liquid outlet. The liquid is 110 delivered under pressure sufficient to overcome this compression action. As the boiler pressure varies, the pressure of the steam in the device varies and the compressing action of the expanding steam on the liquid 115 outlet varies. The device automatically regulates itself as a lower steam pressure permits of an increase in the outflow of oil or other liquid fuel due to the lowered compressing action of the expanding steam on 120 the liquid fuel outlet.

Having thus described my invention, what I claim as new, and desire to secure by Letters Patent is:

1. A burner, including a body portion 130

- having a fuel passage therethrough terminating in an upwardly facing outlet, an expansive fluid passage terminating in a recess adjacent to said outlet, a nozzle piece within 5 said recess and coöperating with said body to define an outlet for the expansive fluid passage in the rear of, separate from, and delivering across said first mentioned outlet, and a member entirely outside of said expansive fluid passage connected to said mouthpiece and extending to the rear of the burner for sliding said mouthpiece along the plane of said fuel outlet. 2. A burner, including a body portion 10 having a fuel passage therethrough terminating in an upwardly facing outlet in a flat surface, an expansive fluid passage terminating in a recess adjacent to said outlet above said surface, a nozzle piece within said recess and coöperating with said surface to define an outlet for the expansive fluid passage delivering across said first mentioned outlet, and a bolt connected to said mouthpiece and extending outside of the fluid passage to the rear of said burner for sliding the mouthpiece in the direction of the length of the burner along said surface. 3. A burner, including a body portion having a substantially flat surface, an upwardly extending wall in the rear of and at an angle to said surface and presenting a recess having a downwardly and inwardly inclined wall, a fuel passage terminating in an outlet in said surface in advance of said recess, and an expansive fluid passage terminating in said recess, a nozzle piece slidable along said surface into and out of said recess and having a portion of its under side spaced from said surface to form an expansive fluid 20 outlet spaced from and in the rear of and directed across said fuel outlet, and means connected to said nozzle piece outside of said expansive fluid passage for forcing the latter inwardly against the downwardly and inwardly inclined side of said recess. 4. A burner including a body portion,
- having a fuel passage therethrough terminating in an upwardly facing outlet, an expansive fluid passage terminating in a recess adjacent to said outlet, a nozzle piece within 50 said recess in the rear of said outlet, and a member coöperating with said body portion and connected to said nozzle piece outside of said expansive fluid passage for retaining said nozzle piece in position. 5. A burner including a body portion, having a fuel passage therethrough terminating in an upwardly facing outlet, an expansive fluid passage terminating in a recess adjacent to but in the rear of said outlet, a 55 nozzle piece within said recess, and a bolt extending lengthwise of said burner and connected to said nozzle piece outside of said expansive fluid passage for retaining said nozzle piece in position. 6. A burner, having a body portion provided with a fuel passage terminating in an outlet, an expansive fluid passage terminating in a recess having a downwardly and inwardly inclined wall, a nozzle piece within 60 said recess and coöperating with said body portion to form an expansive fluid outlet, and a member secured to said nozzle piece and projecting through said inclined wall for holding said nozzle piece tightly against 65 said inclined wall. 7. A burner, having a body portion provided with a fuel passage terminating in an outlet, an expansive fluid passage terminating in a recess having a downwardly and inwardly inclined wall, a nozzle piece within 70 said recess and coöperating with said body portion to form an expansive fluid outlet, and a member secured to said nozzle piece and projecting through said inclined wall at 75 a point spaced from said expansive fluid passage for holding said nozzle piece tightly against said inclined wall.

Signed at New York city in the county of New York and State of New York this 2nd day of June A. D. 1919.

ANNIE H. BEST.
